UNITED STATES PATENT OFFICE.

BERNARD C. CURBY, OF KANKAKEE, ILLINOIS.

WASHING MACHINE.

Application filed September 25, 1922. Serial No. 590,475.

To all whom it may concern:

Be it known that I, BERNARD C. CURBY, a citizen of the United States, residing at Kankakee, in the county of Kankakee and 5 State of Illinois, have invented certain new and useful Improvements in Washing Machines, of which the following is a specification.

This invention relates to washing machines and has special reference to the means for operating washing machines in which the rubbers are constantly agitated. The invention has for its object the provision of means whereby the machine will 10 be automatically operated and may be readily set to run at any desired speed, and also has for its object the provision of means whereby the driving mechanism may be held against movement when the machine is not 15 to operate. The invention also seeks to provide an operating mechanism which will be compact in form and may be readily mounted upon a simple supporting frame so that there will be no waste of space in the practice of the invention. The invention is illustrated in the accompanying drawings and 20 will be hereinafter fully set forth.

In the drawings—

Figure 1 is an elevation of a washing machine having my improvements embodied therein;

Fig. 2 is an elevation viewing the machine at right angles to the viewpoint in Fig. 1, and

Fig. 3 is a detail horizontal section on the line 3—3 of Fig. 1.

In carrying out my invention, I employ a supporting frame 1 which may be of any convenient or preferred form and upon 40 which the tub 2 is placed. The tub is preferably of the circular form illustrated and upon the cover 3 thereof is erected a hollow post 4 in which the dolly shaft 5 is mounted for vertical reciprocation. Disposed approximately radially upon the cover 3 is a bearing bracket 6 in which the crank shaft 7 is journaled, the crank 8 of said shaft being connected by a pitman 9 with an arm or cross-head 10 secured rigidly to and projecting laterally from the upper end of the

dolly shaft 5. Upon the outer end of the shaft 7 is secured a fly wheel 11 and a beveled pinion 12, the fly wheel being provided with an enlargement or weight 13 of any convenient form at a point diametrically opposite to the crank 8 whereby the weight of the crank will be counterbalanced and the shaft 7 permitted to rotate with an even steady motion. Secured upon and rising from the supporting frame 1 is a supplemental frame 14 which is suitably braced, as by bars 15, and a vertical shaft 16 is journaled in and supported by the upper end of the said frame 14 and in a suitable bearing 17 provided upon the main supporting 55 frame 1. To the upper extremity of the shaft 16, I secure a beveled gear 18 which meshes with the beveled pinion 12 whereby the rotation of the vertical shaft 16 will be transmitted directly to the crank shaft 7. 60 To the lower extremity of the shaft 17, I secure a sprocket pinion 19, about which is trained a sprocket chain 20 which is also trained about a gear 21 which will be presently more particularly described. Immediately above the supporting frame 1, a spur pinion 22 is secured upon the shaft 16 and this pinion meshes with a spur gear 23, upon the upper side of which is a locking or brake wheel or disk 24 provided with spaced lugs 80 or teeth 25 upon its upper side. A locking or holding lever 26 is pivotally mounted upon the frame 14 in such position that the lower end 27 thereof may engage between adjacent lugs 25 upon the brake disk 24 and thereby prevent rotation of said disk and, consequently, hold the entire mechanism at rest. Above the spur pinion 22, a spur gear 28 is secured to the shaft 16 and this spur gear 28 meshes with a spur pinion 29 secured upon the lower end of a governor shaft 30. Near the upper end of the governor shaft, a brake disk 31 is slidably fitted thereon and this disk is connected by resilient arms 32 with the hub of the pinion 29, weights 33 being secured centrally to the said resilient arms so that they may move outwardly under centrifugal force in a well-known manner. It will be noted 95 that the governor shaft is rotatably mount- 100

ed at its upper end only within an arm 34 extending from the vertical frame 14. Mounted upon a bracket 35 extending laterally from the vertical frame 14 at the top thereof is a brake lever 36 which has its upper extremity disposed below the brake disk 31, as shown clearly at 37 in Fig. 2, and the lower extremity of the said lever is equipped with a handle or grip 38 and adapted to 10 play adjacent a post or standard 39 upon the main frame. A latch 40 may be engaged in this post 39 at any desired height of the same below the lever so as to limit the downward movement of the outer end 15 thereof and thereby set the upper extremity of the lever at any desired distance below the brake disk 31. Should the rotation of the driving shaft 16 exceed a predetermined speed, the action of the governor will bring 20 the disk 31 into contact with the upper extremity of the lever 36 and the said disk will then act as a brake to retard the rotation of the shaft and, consequently, reduce the speed of the washing machine rubber 25 to the predetermined normal.

The sprocket gear 21 is connected by posts 41 to the top plate 42 of a drum 43 which is enclosed within a casing 44 secured upon the lower portion of the frame 1 below the 30 tub 2, as clearly shown. A central shaft 45 passes loosely through the sprocket gear 21 into the drum and one end of a motor spring is secured to the said shaft within the drum, the opposite end of the spring being secured 35 to the circumferential wall of the drum in a well-known manner. Below the drum, a ratchet wheel 46 is secured to the shaft 45 and is engaged by a pawl 47 mounted in the bottom of the casing 44 and held in engagement with the ratchet by a spring 48. The shaft 45 is a winding shaft and is equipped at its upper end above the sprocket gear 21 with a beveled pinion 49 which meshes with a beveled pinion 50 below the tub and on 40 the inner end of a shaft 51 which extends radially of the tub to the side of the frame 1 opposite that side upon which the frame 14 is mounted. Brackets 52 and 53 are secured to the frame at a point diametrically 45 opposite the frame 14 and these brackets support between them the outer end of the shaft 51, as well as stub shafts, arranged above the shaft 51. A gear 54 is secured upon the outer end of the shaft 51 and meshes 50 with a gear 55 secured upon the lower stub shaft, and the gear 55 in turn meshes with a pinion 56 upon the upper stub shaft, a crank 57 being engaged with the uppermost stub shaft, as shown in Fig. 1.

60 It is thought the operation will be readily understood. When the holding lever 26 has its lower end engaged with the lugs 25 of the holding or locking disk 24, the shaft 16 will be held against rotation and, conse-

quently, the dolly shaft 5 will not operate. 65 While the driving mechanism is thus locked against movement, the crank 57 may be manipulated to transmit motion through the gears 56, 55 and 54 to the shaft 51 and thereby rotate the winding shaft 45 so as to 70 wind the motor spring, the ratchet 46 and pawl 47 serving to hold the spring in its wound condition. After the spring has been wound, if the lever 26 be swung about its pivot, the fulcrum or lower end 27 thereof will be released from the lugs 25 and the spring will then be free to unwind, and, in unwinding, will set up rotation in the drum 43, which rotation will be imparted directly to the gear 21 and thence through 75 the chain 20 to the shaft 16 so that the crank shaft 7 and the governor shaft 30 will be also rotated through the gearing shown and described. The dolly shaft 5 will be thereupon reciprocated vertically 80 within the tub and the required agitation of the clothes therein will be effected so that the clothes will be quickly cleansed.

It will be readily noted that my improved operating mechanism is very simple and 90 compact and does not interfere in any way with the placing of the cover 3 upon the tub nor the removal of the cover from the tub inasmuch as there are no projecting parts above the gears 12 and 18 to interfere with 95 the lifting or lowering of the same. The mechanism is direct acting and may be easily permitted to run at any desired speed, according to the nature of the goods being washed, by merely setting the brake lever 100 36 in the proper position. All the parts of the mechanism are visible at all times so that the action may be observed and access readily had to any parts which may need cleaning, repairing or adjusting.

Having thus described the invention, what is claimed as new is:

1. The combination of a crank shaft, operative connections between the crank shaft and a working element, a beveled gear carried by the outer end of the said shaft, a vertical shaft, a beveled gear carried by the upper end of said shaft below and meshing with the beveled pinion on the crank shaft, a spring motor arranged below the driven machine, and operative connections between the said motor and the vertical shaft for rotating the latter.

2. The combination, of a vertically disposed shaft mounted at the side of a driven machine, gearing connecting the upper end of said shaft with the working element of the machine, a spring motor arranged below the machine and operatively connected with the lower end of said shaft, a governor shaft disposed parallel with the first-mentioned shaft and geared thereto, a brake disk slidably mounted upon the governor shaft,

and a brake lever mounted adjacent the governor shaft and projecting under the brake disk.

3. The combination, of a vertical shaft arranged at the side of a driven machine, gearing connecting the upper end of said shaft with the working element of the machine, a spring motor disposed below the

machine, gearing connecting said motor with the lower end of the vertical shaft, a locking disk geared to the said vertical shaft, and a locking lever mounted above the said disk and having its lower end arranged to lockingly engage the same. 10

In testimony whereof I affix my signature.
BERNARD C. CURBY. [L. s.]
